UNITED STATES PATENT OFFICE

2,607,516

GARMENT HANGER

Bernard Heilman, Detroit, Mich., assignor to L. A. Young Spring & Wire Corporation, Detroit, Mich., a corporation of Michigan

Application February 21, 1947, Serial No. 729,924

4 Claims. (Cl. 223—92)

1.

The main objects of the invention are: First, to provide an efficient garment hanger mainly of paper stock which is strong and rigid and capable of carrying loads to which garment hangers are commonly subjected.

Second, to provide a garment hanger which may, if desired, be shipped in the knockdown and readily set up and assembled for use.

Third, to provide a garment hanger having these advantages which is attractive in appearance and economically produced.

Further objects relating to details and economies of construction and operation will appear from the description to follow. The invention is defined and pointed out in the claims.

A structure showing a prepared embodiment of the invention is illustrated in the accompanying drawing, in which:

Fig. 1 is a side elevation of a garment hanger embodying the features of my invention.

Fig. 2 is an enlarged fragmentary view, partially in vertical section, on line 2—2 of Fig. 4.

Fig. 3 is an enlarged fragmentary view showing the under wall of the outer end portion of a yoke arm of the garment hanger.

Fig. 4 is a fragmentary view in section on the line 4—4 of Fig. 2.

Fig. 5 is an enlarged view in vertical section on the line 5—5 of Fig. 1.

Referring to the drawing, my garment hanger comprises a yoke 1, formed of a paper tube and having downwardly diverging garment supporting arms 2, this yoke in the preferred embodiment of my invention being integrally formed of a paper tube. The outer ends of the arms 2 are vertically collapsed and downwardly inclined to provide shoulder portions 3. The apex 4 of the yoke has the under wall 5 thereof collapsed upwardly longitudinally centrally thereof against the upper wall 6 providing a groove-like recess 7 of substantial length extending longitudinally of the apex 4.

The tube is formed of a plurality of layers or plies of paper as conventionally shown in Figs. 4 and 5, which are desirably convolutely wound into tube formation. The shoulder portions 3, the apex 4, and the other parts of the yoke throughout may be collapsed and curved or conformed to shape in the process of manufacture of the same quite promptly after the tube is formed and before the glue or adhesive used in cementing the plies or layers of paper together has set, the yoke being conformed to its general yoke shape at the same time.

The suspending hook designated generally as 8 is preferably formed of a piece of wire of suitable gauge folded upon itself to provide a hook portion, the bight of the fold constituting the bill 9 of the hook as shown in Figs. 1 and 2. The strands are brought together and twisted in

2.

at least part of the shank portion 10, the lower ends of the strands of the shank being preferably offset at 11 relative to each other. The offset portions 11 terminate in oppositely disposed horizontal arms 12 which are conformed to seat upon the upper wall 6 of the yoke at the apex 4 thereof.

The arms 12 terminate at the outer ends thereof in prongs 13 which are inserted through the holes or openings 14 extending through the upper wall 6, the collapsed lower wall 5 and into the groove-like recess 7 in the lower wall as shown in Fig. 2. The end portions 15 of the prongs 13 beneath the lower wall 5 are bent towards each other and embedded in the longitudinal groove-like recess 7. The dotted line portion of the prongs 13 shown in Fig. 2 shows their position after insertion through the holes 14 and prior to bending into the recess 7. Bending the end portions 15 of the prongs 13 into the groove 7 results in clamping the upper and lower walls of the yoke together, retaining the lower wall in collapsed condition against the upper wall and bracing and fixedly supporting the suspending hook.

By reference to Figs. 1 and 2 it will be noted that the arms 12 above the yoke retainingly engage the yoke for a substantial distance longitudinally thereof, and that the end portions 15 of the prongs are of substantial length so as to be disposed in substantially end abutting relation when in the groove and to supportingly engage the yoke substantially the entire distance between the prong receiving holes 14. This provides substantial support for the yoke at the apex thereof and prevents the bending or collapsing thereof from normal shape when subject to load. The end portions 15 of the prongs being embedded in the groove 7 not only result in effective clamping of the parts but permit grasping of the hanger at the apex without likelihood of injury and objectionable feel to the user. Also by spacing the prong receiving holes 14 at a substantial distance from each other and disposing the end portions 15 of the prongs into close end abutting relation mid-way between the holes, the end portions of the prongs are of a considerable length so as to project a substantial distance below the yoke as shown in dotted outline in Fig. 2. This permits the ready bending of the prong end portions 15 into the groove 7 by hand or by use of any suitable tool, thereby facilitating quick and easy assembly of the suspending hook to the yoke, either by the manufacturer or by the user after shipping in knockdown condition.

The tubular yoke arms 2 intermediate the ends thereof have their vertical side walls 16 adjacent the bottom of the arms collapsed into abutting relation as shown in Fig. 5, and per-

forated at 17 for receiving a safety pin 18 or other suitable securing means for suspending a skirt or other garment therefrom. Also, the collapsed outer ends 3 of the yoke arms may be vertically perforated at 19 for a similar purpose.

The foregoing structures are characterized by the inexpensiveness of production thereof, by their rigidity, resistance to displacement and effectiveness in supporting garments, notwithstanding their simplicity and the inexpensiveness thereof. The operation of assembling the parts may be very rapidly performed with or without the use of tools, and once assembled the hanger is capable of repeated use without likelihood of coming apart or becoming unstable.

An embodiment of the invention which incorporates the principle of the invention in a highly desirable manner has been illustrated and described. It should be understood that the foregoing terminology is used descriptively rather than in any limiting sense, and with full intent to use equivalents of the features shown and described within the scope of the following claims.

Having thus described my invention, what I claim as new and desire to secure by Letters Patent is:

1. In a garment hanger, the combination of a supporting yoke and a suspending hook, said yoke being of tubular cross section and of fibrous material and having downwardly diverging garment supporting arms, the underwall of the yoke at the apex thereof being upwardly collapsed longitudinally centrally thereof to provide a downwardly facing groove-like recess extending longitudinally of the yoke, said yoke having vertical apertures therethrough substantially spaced longitudinally thereof and intersecting said groove-like recess, said suspending hook being formed of wire folded upon itself with the bight of the fold constituting the bill of the hook, the strands of the folded wire being twisted together at the shank and laterally offset below the twist and terminating in oppositely disposed arms of substantial length seatingly engaged upon the upper wall of the yoke at the apex thereof, said arms terminating in downwardly projecting prongs disposed through said apertures, the end portions of the prongs being bent towards each other into said groove-like recess and into supporting engagement with the under wall of the yoke, the bent over end portions of the prongs being of substantial length to supportingly engage the underwall of the yoke substantially the entire distance between said apertures and to facilitate bending the same into said supporting engagement with the under wall, said arms, prongs and bent over end portions constituting means for clampingly retaining said underwall in collapsed condition against the upper wall of the yoke.

2. In a garment hanger, the combination of a supporting yoke and a suspending hook, said yoke being of tubular cross section and of fibrous material and having downwardly diverging garment supporting arms, the underwall of the yoke at the apex thereof being upwardly collapsed longitudinally centrally thereof to provide a downwardly facing groove-like recess extending longitudinally of the yoke, said yoke having vertical apertures therethrough substantially spaced longitudinally thereof and intersecting said groove-like recess, said suspending hook being formed of wire folded upon itself with the bight of the fold constituting the bill of the hook, the strands of the folded wire being twisted together at the shank and laterally offset below the twist

5 and terminating in oppositely disposed arms of substantial length seatingly engaged upon the upper wall of the yoke at the apex thereof, said arms terminating in downwardly projecting prongs disposed through said apertures, the end portions of the prongs being bent towards each other into said groove-like recess and into supporting engagement with the underwall of the yoke, said arms, prongs and bent over end portions constituting means for clampingly retaining said underwall in collapsed condition against the upper wall of the yoke.

3. In a garment hanger, the combination of a supporting yoke and a suspending hook, said yoke being of tubular cross section and of fibrous material and having downwardly diverging garment supporting arms, the underwall of the yoke at the apex thereof being upwardly collapsed longitudinally centrally thereof to provide a downwardly facing groove-like recess, said yoke having vertical apertures therethrough substantially spaced longitudinally thereof and intersecting said groove-like recess, said suspending hook having a hook portion and a shank terminating in oppositely disposed arms of substantial length seatingly engaged upon the upper wall of the yoke at the apex thereof, said arms terminating in downwardly disposed prongs projecting through said apertures, the end portions of the prongs being bent towards each other into said groove-like recess and being of substantial length to supportingly engage the underwall of the yoke substantially the entire distance between said apertures, and to facilitate bending the same into said supporting engagement, said arms, prongs and bent over end portions constituting means for clampingly retaining said underwall in collapsed condition against the upper wall of the yoke.

4. In a garment hanger, the combination of a supporting yoke and a suspending hook, said yoke being of tubular cross section and of fibrous material and having downwardly diverging garment supporting arms, the underwall of the yoke at the apex thereof being upwardly collapsed longitudinally centrally thereof to provide a downwardly facing groove-like recess, said yoke having vertical apertures therethrough substantially spaced longitudinally thereof and intersecting said groove-like recess, said suspending hook having a hook portion and a shank terminating in oppositely disposed arms of substantial length seatingly engaged upon the upper wall of the yoke at the apex thereof, said arms terminating in downwardly disposed prongs projecting through said apertures, the end portions of the prongs being bent towards each other into said groove-like recess into supporting engagement with the underwall of the yoke, said arms, prongs and bent over end portions constituting means for clampingly retaining said underwall in collapsed condition against the upper wall of the yoke.
